By B. Singer, Atty.

UNITED STATES PATENT OFFICE.

SIMON HICKEY, OF MARRICKVILLE, NEW SOUTH WALES, AUSTRALIA.

AUTOMATIC ALARM.

1,415,874.

Specification of Letters Patent.

Patented May 16, 1922.

Application filed August 24, 1920. Serial No. 405,653.

To all whom it may concern:

Be it known that I, SIMON HICKEY, a subject of the King of Great Britain and Ireland, residing at "Arcadia," Harrington 5 Street, Marrickville, in the State of New South Wales, Commonwealth of Australia, have invented certain new and useful Improvements in Automatic Alarms, of which the following is a specification:

10 The object of this invention is to provide a simple, effective and inexpensive device for calling attention to the surreptitious opening of a door or window or the unauthorized interference with a movable object 15 and for similar purposes.

The essential features of my device are a clockwork mechanism (of the nature hereinafter described) designed to operate an alarm of ordinary construction, a centrally pivoted detent lever controlling the movement of the hammer and releasable by the pulling of a flexible cord or chain connected thereto for the purpose herein set forth.

The clockwork mechanism resembling that 25 of an ordinary clock, actuates a saw-toothed wheel geared to an escapement device the pallet of which is centrally mounted on an oscillating element which also carries the shank of the hammer.

30 As soon as the spring is wound up the mechanism rotates the toothed wheel which in turn actuates an escapement oscillating the pivot-pin and causing the hammer to strike the gong.

35 The detent lever carries on one end a retaining pin designed to engage with an arm (projecting from said pivot pin) in such a manner as to hold the same and prevent its oscillation thus controlling and preventing 40 the gong from sounding.

But in order that the invention may be more clearly understood I will refer to the accompanying drawings in which—

Fig. 1 is a perspective view of my device 45 enclosed in a convenient box or casing with the detent lever pulled "off" and the parts free to operate.

Fig. 2 is a front elevation showing the parts locked.

50 Fig. 3 is side elevation showing the casing in section and with the parts in the locked position.

The clockwork mechanism is of ordinary construction consisting of a winding stem A, 55 spring A', toothed wheel A², pawl A³ and ratchet wheel A⁴. The toothed wheel gears

with a pinion B on a pivot-pin B' carrying a serrated wheel B² which is engaged by the pallet C centrally fixed on the sleeve D oscillating about a standard D'. Said sleeve 60 also carries the shank E of hammer E'. From the opposite side of the sleeve D extends an arm E² which may be a continuation of the hammer shank E. The detent lever F is centrally pivoted at G on the top- 65 plate H, and carries at one end the retaining pin F' designed to engage with and hold the arm E² as shown in Fig. 2. The mechanism above described is mounted upon a base N.

70 The cords J and J' are connected respectively to the ends of the detent lever and are so disposed that a pull on either of them will swing the end of the lever carrying the retaining pin clear of the arm E² and, 75 releasing same, permit the clockwork mechanism to actuate the oscillating pin D.

The cord K is for the purpose of pulling the detent lever "on" (i. e. with the retaining pin F' engaging arm E².) when the device is placed in a position not easily accessible for manipulation but would not be required under other circumstances, similarly the weight L is provided for the purpose of being placed in a position where an unauthorized movement would cause it to drop and pull the detent lever "off" causing the alarm to operate.

80 The operation of my invention is as follows:—

90 The mechanism having been wound up, the detent lever is brought into the holding position (i. e. that in which the retaining pin is in contact with the arm E²) and one or both of the cords J, J' so fastened to a 95 door or other movable object the movement of which it is desired to detect, that such movement will cause one of said cords to pull the said lever "off" so that the retaining pin is withdrawn from contact with the 100 arm E². The mechanism being thus freed, oscillates the sleeve D and causes the hammer to come into striking contact with the gong M—thus giving the required alarm.

105 What I claim and desire to secure by Letters Patent is:—

1. An alarm device, comprising in combination spring actuated mechanism, means for tensioning the spring, a serrated wheel actuated by said mechanism, a pallet centrally mounted on an oscillating sleeve and actuated by the serrated wheel, a hammer-

shank projecting from said sleeve, a head on said shank, a stop arm for said shank, a gong associated with said head, a detent lever pivoted at a point between its ends, and having 5 a member to engage said stop arm and restrain said hammer shank from operating when said detent lever is in one position and a cord connected to the detent lever and so directed that a pull thereon will move said 10 lever to the "off" position.

2. An alarm device, comprising in combination a base, a plate supported thereon, spring actuated mechanism located between said base and plate, means for tensioning the 15 spring, a spindle having end bearings in said base and plate and rotated by said mechanism, a serrated wheel on said spindle, an oscillating sleeve about a standard between said base and plate, a hammer shank 20 extending in one direction and an arm ex-

tending in another direction from said sleeve, a head on said hammer shank, a gong associated with said head and mounted on the base, a pallet affixed on said sleeve, said pallet engaging said serrated wheel and 25 being oscillated thereby to effect oscillation of said hammer-shank and arm, a detent lever pivoted on said plate, and having means engaging said arm to prevent oscillation thereof when the lever is in one ex- 30 treme position, a cord connected to said lever and a weight on the end of said cord, said weight when hanging on said cord pulling said lever from said extreme position and releasing the mechanism to operate the ham- 35 mer and sound the gong as herein set forth.

Signed at Sydney, N. S. W. this nineteeneth day of July A. D. 1920.

SIMON HICKEY.
